BY

UNITED STATES PATENT OFFICE.

HERMANN NEEF, OF JEFFERSON CITY, MISSOURI.

STOVE-HOOD.

SPECIFICATION forming part of Letters Patent No. 399,430, dated March 12, 1889.

Application filed April 14, 1888. Serial No. 270,627. (No model.)

To all whom it may concern:

Be it known that I, HERMANN NEEF, of Jefferson City, in the county of Cole and State of Missouri, have invented a new and Improved Stove-Hood, of which the following is a full, clear, and exact description.

My invention has for its object the conveyance of the steam, smoke, and disagreeable odors arising in the process of cooking and washing on a stove or range to the chimney or other flue, thus preventing the spread of the vapors through the house. I therefore term it the "kitchen-purifier."

My invention consists in the construction and combination of the several parts, as will be hereinafter set forth, and pointed out in the claim.

Reference is to be had to the accompanying drawings, forming a part of this specification, in which similar letters of reference indicate corresponding parts in both figures.

Figure 1 is a perspective view of my invention. Fig. 2 is a sectional elevation of same through the center of the flues.

A is the top plate of a cooking stove or range; B, smoke-flue thereof, with horizontal extension b extending to chimney; C, a cone-shaped hood large enough to cover a portion of the top plate, A, of the stove. The upper part of the hood C is provided with a section of a pipe, c, and above this is another section of pipe, c', of a larger diameter, within which section c slides. Above section c' is another pipe-section, c'', of larger diameter, within which section c' slides. The upper part of section c'' has an elbow, b', and is bent horizontally and forms part of the extension-pipe b, within which is a damper, f, arranged as shown. Any desired number of such sections may be employed.

Preferably the hood C will be detachably connected with the pipe-section c by a bayonet-joint, the hood being provided with a short pipe-section, c³, provided with studs engaging L-shaped slots in the lower end of section c, and the upper end of section c may be provided with a semicircular extension, c⁴, adapted to fit the upper portion of extension b. With this construction the damper f may be dispensed with.

The sections c c' c'' are made telescopic, or, in other words, they slide one within the

other. Thus, when it is desired to raise the hood C, the section c slides within section c', and if the hood is raised above the length of section c, then section c' slides within section c'', and thus any desired adjustment of the hood C may be effected. The hood is counterbalanced and held in any desired position of adjustment by the weight D and wire, rope, or chain d, which passes over pulleys e e' down through the pipe-sections, the extremity of the rope being attached at i to the inner surface of pipe-section c, as shown in Fig. 2. The pulleys may be attached to the walls of the apartment, as desired.

The outer lower edges of hood C are provided with grooves h, in each of which a removable wing, E, is carried, the upper end of each wing being bent into hook form. When not in use, the wings E occupy the position shown in Fig. 2. When in use, the hook part g of the wing is inserted in the groove h, and the lower part of the wing will then project downward and outward from the hood, as shown in dotted lines, Fig. 1, the wings, when thus arranged, forming an enlargement of the hood, so that nearly the whole top of the stove may be covered by the hood should it be desired.

The hood may, when desired, be furnished with wire gage ventilators k, as shown.

The damper f is provided to cut off the connection between the pipe-sections c c' c'' and pipe b when the fire is being kindled and the full draft of the chimney is wanted for the smoke-pipe B. The damper will also admit of any proportionate division of the chimney-draft between the sections c c' c'' and the smoke-pipe, accordingly as it is partially opened and closed.

If for any reason, as a poor chimney-draft, it is not desired to connect the hood C with the smoke-flue used for the stove or range, the required hood-connection may be made with any other flue of the chimney.

The operation of my invention is as follows: The hood C being counterbalanced by the weight D, the hood may be readily raised or lowered and set to the desired position above the top of the stove, and on opening the damper f an upward draft through the hood into the chimney or flue will be maintained, by which all the fumes, vapors, and odors will

be at once drawn and carried away into the chimney and prevented from escaping into the apartment. By the arrangement of the wire rope within the pipe-sections the weight 5 has a direct perpendicular pull or action upon the sections, and they are prevented from getting out of line, while the rope is out of the way and the exterior of the pipe is cleared of all obstructions.

10 Having thus described my invention, what I claim as new, and desire to secure by Letters Patent, is—

The hood constructed with edge grooves, *h*, in combination with the independent wings *E*, constructed in hook form at their upper 15 edges, as described, whereby the lower edges of said wings may be supported in the grooves when in open position, and the hooked edges of the wings may hang in the grooves when in closed position, as set forth.

HERMANN NEEF.
